(57) **CLAIM**

We claim the ornamental design for a shower head with arm, as shown and described.

DESCRIPTION

FIG. 1 is a front isometric view of a shower head with arm; FIG. 2 is a rear isometric view of the shower head with arm of FIG. 1;

FIG. 3 is a front elevation view of the shower head with arm of FIG. 1;

FIG. 4 is a rear elevation view of the shower head with arm of FIG. 1;

FIG. 5 is a top plan view of the shower head with arm of FIG. 1;

FIG. 6 is a bottom plan view of the shower head with arm of FIG. 1;

FIG. 7 is a right side elevation view of the shower head with arm of FIG. 1; and,

FIG. 8 is a left side elevation view of the shower head with arm of FIG. 1.

The broken lines shown in the drawings are only for purposes both of illustrating use and environment and to define the bounds of the claimed design and form no part of the claimed design.
